UNITED STATES PATENT OFFICE.

JOHN C. KUPFERLE, OF ST. LOUIS, MISSOURI.

DESIGN FOR A HYDRANT.

SPECIFICATION forming part of Design No. 16,727, dated June 8, 1886.

Application filed April 5, 1886. Serial No. 197,887. Term of patent 14 years.

To all whom it may concern:

Be it known that I, JOHN C. KUPFERLE, of the city of St. Louis, Missouri, have invented and produced a new and original Design for 5 Hydrants, of which the following is a specification, reference being had to the annexed drawings, making a part thereof.

Figure 1 is a side elevation of my newly-designed hydrant, and Fig. 2 is a view in perspective, the two views in conjunction serving to more fully illustrate my design.

The same letters of reference denote the same parts.

The leading features of my design are the 15 shape and configuration of the cap, nozzle, and body or casing.

In the illustration the body or casing is marked A; and the configuration of the several parts are thus described, beginning at the upper end of the structure: The cap C has wings c c, that project, respectively, to the right and to the left of the casing-body, as viewed in front; secondly, the vertically-fluted upper portion, a, of the casing A terminates in the 25 horizontal band a'; thirdly, the longitudinally-fluted nozzle E, whose bent extremity e projects,

at an obtuse angle from the horizontal part e'; fourthly, the vertically-fluted main portion a² of the casing A commences below the band a' and extends downward and terminates in the 30 molding a³ and base a⁴. The portion a² tapers upward slightly, and the base is angled.

I claim—

1. In a design for a hydrant, the design for the upper part, as herein described and shown, 35 the same consisting of the vertically-fluted portion a, longitudinally-fluted nozzle E, having downwardly-bent extremity e, the said portion a being provided with the cap C, having laterally-projecting wings c c, as set forth. 40

2. The design for a hydrant herein described and shown, the same consisting of a hydrant body or casing, A, having the base a⁴, molding a³, vertically-fluted tapering portion a², band a', the upper portion, a, terminating in cap C, having laterally-projecting 45 wings c c, as set forth.

Witness my hand this 1st day of April, 1886.

JOHN C. KUPFERLE.
